(57) **CLAIM**

The ornamental design for control handle for pneumatic devices, as shown and described.

DESCRIPTION

FIG. 1 is an isometric view of a control handle showing my design;

FIG. 2 is a front view of FIG. 1;

FIG. 3 is a top view of FIG. 1;

FIG. 4 is a left side view of FIG. 1;

FIG. 5 is a right side view of FIG. 1;

FIG. 6 is a bottom view of FIG. 1; and,

FIG. 7 is a back view of FIG. 1.

The broken lines which define the bounds of the claimed design form no part thereof.
